POUR PAIL

Charles H. Rollason, Los Angeles, Calif., assignor
to Boyle Manufacturing Company, Inc., Los
Angeles, Calif., a corporation of California

Application September 26, 1934, Serial No. 745,495

4 Claims. (Cl. 221—19)

My invention relates to an improved pour pail of the type in which a tamper-proof spout is provided to safeguard the genuineness of the contents thereof until the package reaches the 5 ultimate user.

My invention relates to pails, drums or containers of the type which have a full opening and a cover therefor, adapted to be permanently fastened in place after the container has been 10 filled through said full opening. The cover is provided with a smaller pour opening which is originally closed or sealed against tampering, but which is easily opened by the ultimate consumer for removal of the contents.

15 The object of the invention is to provide the cover with a weakened or scored portion which requires breaking to form a pour opening through which the contents can be poured.

20 A further object is to provide a pour lip or spout in association with the pour opening adapted to properly direct the liquid pouring from the opening.

25 A further object is to provide suitable self-contained closure means by which the pour opening can be effectively closed to prevent the entrance of dirt from the outside in the event that it is not desired to pour out all of the contents at one time.

30 A further object is to provide a structure which adds very nominally to the cost of manufacture of the pail or container.

35 These and other objects of my invention will appear from the following description and claims in conjunction with the accompanying drawings which illustrate several embodiments of the invention.

Referring to the accompanying drawings,

40 Fig. 1 is an elevational view of the upper portion of a pail including the cover and showing the pour lip and closure lid or cover therefor;

Fig. 2 is an enlarged section substantially on the line 2—2 of Fig. 1;

Fig. 3 is a detail section on line 3—3 of Fig. 2;

45 Fig. 4 is a top plan view of the pour opening and lip or spout construction of Fig. 1, showing the hinged lid in open position;

Fig. 5 is a section on the line 5—5 of Fig. 4;

Fig. 6 is a top plan view of a modification in 50 which the opening in cover metal is controlled by a rotary valve member, the valve being shown in closed position and sealed;

Fig. 7 is a view similar to Fig. 5, illustrating the valve in open position; and

55 Fig. 8 is an enlarged section on the line 8—8 of Fig. 7.

The upper portion of a typical sheet metal pail or container A is shown comprising a cylindrical structure of sheet metal open to the full extent of its diameter, so that it can be quickly and easily filled. The upper rim of the wall of the pail is 5 turned over to form an annular bead 1 for strength and for the securing of the cover B thereto after the pail has been filled.

The cover B is made of sheet metal and is generally dish shape in form. Its marginal edge is 10 likewise formed with a bead 2 which is crimped or contracted around the bead 1 of the pail by suitable machinery to seal the joint after the pail has been filled.

The cover has a flattened inclined portion 3 15 adjacent one edge to accommodate a pour lip or spout below the top level of the cover, so that the pails may be stacked. Adjacent the edge of the cover, the metal of the flat portion 3 of the cover is scored or weakened on a curved line 4 so that 20 the sheet metal may be easily broken or separated on this line by any convenient bar or other tool. The score line preferably defines a circle with the exception of the portion between the ends 5 of the line, so that the metal will bend on a substantially straight line between these ends when the circular portion 6 of the metal is severed on the scored line. Thus while the metal is unbroken on the scored line the pail is closed, but when the scored portion is severed or broken, 30 and then bent inwardly and at an angle, as shown more clearly in Fig. 5, an almost circular pour opening 7 is provided from which the contents of the pail can be poured.

The scored portion 5 is provided in the bottom 35 flat wall of a circular depressed or dished portion formed in the metal wall of the cover, so that a spout or pour lip member of sufficient depth may be provided without extending above the level of the top of the cover. The annular 40 side wall 8 of this dished portion is substantially at right angles to the plane of the flat portion 3 of the cover and is larger in diameter than the score line 4 so as to leave a portion 9 of the bottom wall forming a flange surrounding the 45 pour opening.

This construction also provides a suitable means for mounting and fastening the pour lip member in position. The pour lip or spout member C is a trough-like member open at its 50 top and outer end, and generally rounded in cross section to properly direct the flow of liquid from the pour opening. The outer end projects slightly beyond the edge of the cover, and the trough is generally tapered to a smaller end to 55

properly control the stream therefrom. The upper edges 10 of the trough portion are straight for the major portion and then incline upwardly slightly, merging in a round formation at the 5 inner end of the member. The top and outer end of the lip or spout member is adapted to be closed by a hinged cover or lid D which consists of a flat piece of metal bent to conform to the upper edge of the spout member so that it will 10 fit said edge and form a tight joint when the lid is down. The tightness of this joint is assisted by a marginal flange 11 around the lid, the outer portions 12 of which are wider and are formed as ears to resiliently engage the side walls of the 15 spout, the formation being such that when the lid is pressed downwardly the ears 12 will be sprung apart by the upper edges of the spout, and after the ears pass said edges, they spring toward each other and act upon the rounded 20 wall of the spout in a manner tending to draw the lid tightly against the upper edges of the spout. This action also locks the lid in closed position. The outer end of the lid also has a downturned flange 13 which overlies the end of 25 the spout and engages the edge thereof to form a tight joint.

This flange has an indented bead 14 which snaps under the edge of the spout and holds the flange tightly against the edge. This flange also 30 has an ear extension 15 forming a finger piece which may be conveniently gripped to lift the lid. The lid, as shown, can be swung upwardly and inwardly to a position against the top wall of the cover so as to be entirely clear of the spout 35 when the contents are poured therefrom. The inner end of the lid has a hinge for this purpose, the hinge being formed by bending an ear portion 16 around a slotted ear 17 on the edge of the spout member. The metal of the cover has 40 a bead 18 formed upwardly to bear against the hinge and support the slotted ear 17 against being bent accidentally.

The inner end of the spout member has a dish-shaped portion conformed to the dished portion 45 of the cover so as to fit therein for the purpose of adapting the spout to the pour opening. The spout member is fastened in place after the two dished parts are nested, by forming several peripherally spaced registering interlocking beads 50 20 in the side walls of both dished portions as shown in Figs. 2 and 3. The dished portion of the spout member has its bottom wall removed to provide a circular opening 21 slightly larger in diameter than the score line 4 which defines 55 the pour opening.

In the modified embodiment illustrated in Figs. 6 to 8, the hinged lid is not relied upon to 60 close the pour opening, but is simply intended as a cover to keep out foreign matter from the spout. Instead a rotary valve member 22 is provided in association with the pour opening. This valve is in the form of a flat disc having a 65 transverse upstanding rib 23 by which it may be rotated. The disc is positioned between the bottom wall flanges of the dished portions of the cover and spout member, as shown in Fig. 8, the space 24 between these flanges being made sufficient to allow the disc to be rotated easily in its own plane. In this case, the pour opening 7 is 70 made smaller and is defined by the semicircular score line 4. The disc valve also is provided with a similar shaped opening 25 which is adapted to be brought into and out of registration with the pour opening by the rotation of 75 the disc, to open and close the pour opening.

In this modified structure means are provided to seal the disc valve in closed position if desired. The bottom wall of the dished portion of the spout has an ear or lug 26 formed up and provided with a hole 27 adapted to register with a hole 28 in the rib 23 of the disc when the disc is in closed position. A sealing device in the form of a wire 29 is looped through these holes and fastened by the usual sealing lead. 5

In this case the pour opening in the pail cover 10 can be formed originally, and the closed and sealed valve can be relied upon to render the structure tamper-proof.

I claim:

1. In a structure of the class described, the 15 combination of a container having a cover of sheet metal, a dish-shaped depression in the sheet metal of said cover having a side wall provided with a plurality of peripherally spaced outward projections and having in its bottom wall 20 a score line upon which the sheet metal is adapted to be severed and bent inwardly to define a pour opening, a spout for directing the fluid from said pour opening and comprising a trough-like member having a dish-shaped body portion 25 having a side wall provided with a plurality of peripherally spaced outward projections registering with the said projections in said cover, whereby said spout is permanently secured against rotary movement in said depression, and 30 a hinged cover for said spout having means for effecting a resilient spring engagement with the side and end edges of the spout to form a releasable closure therefor.

2. In a structure of the class described, the 35 combination of a container having a cover of sheet metal, a dish-shaped depression in the sheet metal of said cover having in its bottom wall a score line upon which the sheet metal is adapted to be severed and bent inwardly to define a pour 40 opening, a spout for directing the fluid from said pour opening and comprising a trough-like member having a body portion secured in said depression, and a rotary valve disc in said depression movably confined between the same and the body portion of said spout, said disc having an opening adapted to be brought into and out of registration with the pour opening to control 45 said pour opening.

3. In a structure of the class described, the 50 combination of a container having a cover of sheet metal, a dish-shaped depression in the sheet metal of said cover having in its bottom wall a score line upon which the sheet metal is 55 adapted to be severed and bent inwardly to define a pour opening, a spout for directing the fluid from said pour opening and comprising a trough-like member having a body portion secured in said depression, a rotary valve disc in 60 said depression movably confined between the same and the body portion of said spout, said disc having an opening adapted to be brought into and out of registration with the pour opening, and means for 65 sealing said disc against rotation relative to said spout when said pour openings are out of register.

4. In a structure of the class described, the 70 combination of a dish-shaped container and a dish-shaped cover therefor and a flattened inclined portion, the metal in said flattened portion having a circular depressed portion the bottom wall of which has a weakened or scored line on which the metal is adapted to be severed 75

222. DISPENSING.

to form a pour opening, a dish-shaped member fitted within said depressed portion and having an opening in its bottom wall corresponding to the pour opening, said dish-shaped member having a laterally extending trough-like portion communicating therewith and forming a pouring spout for directing the fluid from the pour opening, a cover member for said dish-shaped mem-

ber and pouring spout comprising a flat member hinged on the dish-shaped member and adapted to contact the edges thereof and said pour lip to form a closure therefor, and means on said hinged cover member for effecting a releasable spring engagement with the side and end edges of said pouring spout.

CHARLES H. ROLLASON.
